UNITED STATES PATENT OFFICE.

HERMAN F. BUSCH, OF MILLVALE, PENNSYLVANIA, ASSIGNOR TO ARMSTRONG CORK COMPANY, OF PITTSBURGH, PENNSYLVANIA, A CORPORATION OF PENNSYLVANIA.

STOPPER OR CORK AND METHOD OF MAKING THE SAME.

Application filed July 21, 1924. Serial No. 727,167.

The present invention relates broadly to closures for receptacles, and more particularly to so called stoppers or corks for bottles or jars and to a method of making the same.

There is a growing demand for stoppers or corks of the nature herein contemplated capable of being embossed or otherwise provided with indicia indicating the manufacturer, quality of the goods, or the like. It has been found that composite stoppers having a compressed wooden disk and a cork secured thereto are generally unsatisfactory due to the prevalent custom among bottlers of soaking the corks. This soaking not only permits the disks to expand to their normal condition thereby substantially obliterating any indicia which they may have carried, but frequently results in loosening the corks. With certain goods there is a necessity of effecting as tight a closure as possible, whereby evaporation, contamination or injury to the goods is prevented. Frequently a sufficiently tight closure cannot be produced by the use of a cork only, due to imperfections either in the cork or in the neck of the bottle or jar.

The present invention not only provides a stopper or cork permitting the addition of such indicia as may be desired, but also one which is substantially indestructible, relatively inexpensive, and capable of effecting a tight closure.

In the accompanying drawings there are shown for purposes of illustration only certain preferred embodiments of the present invention together with one means admirably adapted for effecting the assembly of the corks, it being understood that the drawings do not define the limits of my invention as changes in the construction and operation disclosed therein may be made without departing either from the spirit of the invention or the scope of my broader claims.

In the drawings,

Figure 1 is an exploded view illustrating the sheathing, the cork and annulus in position to be assembled, the sheathing having an adhesive substance therein;

Figure 2 is a vertical sectional view through the parts after assembly, but before compression of the annulus;

Figure 3 is a view similar to Figure 2 illustrating the parts after compression of the annulus;

Figures 4 and 5 are views similar to Figures 2 and 3 respectively but illustrating a thinner annulus;

Figure 6 is a vertical sectional view through the upper portion of a bottle having a stopper constructed in accordance with Figure 3 in position therein, and

Figure 7 is a vertical sectional view through one form of plunger and die suitable for holding, compressing, and assembling the parts.

It has heretofore been proposed in the art to which the present invention relates to construct stoppers having a central cork with a surrounding annulus either with or without a metal sheathing. Ordinarily, however, the corks and annuli employed in connection therewith have been of different material, the annuli usually not being of material permitting substantial compression or capable of effecting any substantial sealing. It is one of the objects of the present invention to construct a stopper in which the annulus possesses the characteristics not only permitting it to be compressed but causing it to also serve as a sealing means.

In accordance with the embodiment of the invention illustrated in Figures 1 to 3 and Figure 6 the stopper may comprise a cup shaped metal sheathing 2 preferably having corrugated edges 3 permitting the same to be crimped inwardly, the sheathing being adapted to receive a cork 4 and an annulus 5.

Conveniently, a small amount of suitable adhesive as indicated at 6 may be placed within the sheathing and the cork 4 then placed in position with its larger end in engagement with the adhesive. Thereafter the annulus 5 is forced downwardly over the cork serving not only to center the cork but to preliminarily hold the same in position within the sheathing. In the figures of the drawing referred to, the annulus 5 has a thickness slightly greater than the depth of the cup shaped sheathing, whereby a portion of the annulus projects above the edge 7 of the sheathing to form a sealing surface 8. After the parts have been brought into the assembled relationship shown in Figure 2 the assembly may be placed within a suitable die 9 serving to center the sheathing. Thereafter a central plunger 10, conveniently urged downwardly by a spring 11 is brought into contact with the smaller end of the cork, and an inter-

100
105
110
115

mediate sleeve 12 normally urged downwardly by a spring 13 is brought into contact with the sealing surface 8 of the annulus 5. Thereafter the outer sleeve or 5 plunger 14 is lowered in any desired manner to bring its inclined crimping surface 15 into engagement with the sheathing and crimp it inwardly from a position shown in Figure 2 to that shown in Figure 3. This 10 not only tends to lock the annulus in position, but compresses it inwardly against the cork 4 and together with the adhesive 6 effectively resists separation or removal of the cork.

15 In accordance with the preferred embodiment of the present invention the cork 4 will be made in accordance with the present standard practice while the annulus 5 will conveniently comprise a body of either natural or artificial cork or other compressible 20 material capable of contacting with the upper edge of a bottle or jar neck to form a closure therefor.

25 In Figures 4 and 5 there is illustrated a slightly modified embodiment of my invention in which the parts corresponding to parts heretofore described are designated by the same reference characters having a prime added thereto. In this modified showing, 30 the annulus 5' has a thickness equal to or less than the depth of the cup shaped sheathing 2' whereby when the parts are compressed into the position shown in Figure 5 the metal sheathing will substantially 35 close the entire edge of the annulus.

In caps as usually constructed, there is a slight convexity to the upper portion of the cap. Preferably the sheathing 2 will have a similar configuration whereby this convexity 40 forms a small recess for the distribution of the adhesive material 6.

The advantages of the present invention arise from the provision of a stopper com-

prising a cork and a compressed annulus co-operating therewith and surrounding the 45 cork.

Further advantages of the present invention arise from the provision of a stopper of the character referred to having a protective sheathing adapted to carry suitable advertising or descriptive indicia. 50

I claim:

1. As an article of manufacture, a compressible stopper, a compressible annulus surrounding the same, and a means for holding a portion of said stopper and the annulus in a state of compression. 55

2. As an article of manufacture, a cork stopper, an annulus of compressible material surrounding the same, and a cup shaped 60 metal sheathing maintaining the annulus and a portion of the stopper in a state of compression.

3. As an article of manufacture, a stopper comprising a sealing cork and a cork annulus surrounding the same, and means for holding a portion of said sealing cork and the annulus under compression. 65

4. As an article of manufacture, a stopper comprising a sealing cork, a cork annulus surrounding a portion of the sealing cork, a cup shaped sheathing holding said annulus and a portion of a sealing cork in a state of compression and an adhesive between the 70 sealing cork and the sheathing. 75

5. As an article of manufacture, a stopper comprising a compressible plug, a compressible annulus surrounding the plug, and a cup shaped sheathing having its flange 80 pressed against the annulus to secure the parts together, the greatest pressure being exerted on the annulus and plug in a plane of the sheathing near the lower edge of the flange of the sheathing. 85

HERMAN F. BUSCH.
